UNITED STATES PATENT OFFICE.

OLIVER S. HUTCHINSON, OF NEW LENOX, MASSACHUSETTS.

CARRIAGE-FEEDING DEVICE FOR SAW-MILLS.

SPECIFICATION forming part of Letters Patent No. 286,201, dated October 9, 1883.

Application filed April 17, 1883. (No model.)

To all whom it may concern:

Be it known that I, OLIVER S. HUTCHINSON, a citizen of the United States, residing at New Lenox, in the county of Berkshire and State 5 of Massachusetts, have invented new and useful Improvements in Carriage-Feeding Devices for Saw-Mills, of which the following is a specification.

This invention relates to improvements in 10 the carriage-feeding devices of circular saw-mills, the object being to reduce and simplify the number of parts of such devices, whereby the carriage is moved in both directions through the instrumentality of a single pulley, 15 combined with peculiarly-operating mechanism for governing the movements of said pulley.

In the drawings, forming part of this specification, Figure 1 is a plan view of a saw-mill embodying my improvements. Fig. 2 is a 20 side elevation, partly in section; and Figs. 3, 4, and 5 are detail views.

In the drawings, A indicates the frame of the husk. *i i* are the string-pieces, and *i' i' i'* are the head-blocks, of the carriage. *t* is the rack. 25 *c* is the main shaft. *B* is the driving-pulley. *v v'* are cone-pulleys. *e* and *w* are connecting-belts. *n* and *u* are feed-shafts. *y* and *D* are feed-pulleys. *z* is an idler. *o* is a hand-lever. *x* and *d* are arms on lever *o*. *m* is a movable 30 box for shaft *n*.

The carriage string-pieces *i* of this machine consist of wrought-iron continuous strips of double T shape in cross-section, instead of wooden pieces, as ordinarily made, whereby 35 greater rigidity and durability of the carriage are obtained. Said string-pieces are united by the iron head-blocks *i'*. The usual rack, *t*, is secured to the lower edge of one of pieces *i*, and a pinion on the end of shaft *a* engages 40 with said rack.

The shaft *a* is suitably supported in the husk, and has the pulley *D* secured to its inner end. Said pulley *D* is provided with a deep groove, as shown, and with a bearing-face on each side 45 of said groove. The belt *e*, running from the pulley *h* on the main shaft *c*, revolves pulley *D* in one direction when caused so to do by the operator. A shaft, *n*, is located on said husk, and has one end extending over said 50 pulley *D*, and having a bearing in a vertically-movable box, *m*, said shaft *n* having fixed

thereon the pulley *y*. Said pulley *y* has a rib, 4, projecting from its face, and said rib and the parts 3 of the face of said pulley each side of rib 4 are adapted to bear jointly on the 55 face of pulley *D* and in the upper part of the groove therein. The groove in pulley *D* is of such depth that the passage of belt *e* around it when pulleys *y* and *D* are in contact is not interfered with. Cone-pulleys *v v'* are placed 60 on shaft *c* and on shaft *n*, whereby different degrees of speed may be given to the latter. A hand-lever, *o*, is pivoted beneath pulleys *y* and *D*, and has thereon an arm, *d*, bearing on its end the idler *z*, adapted to be operated 65 against belt *e* to tighten it. A second arm, *x*, of curved form, passes through an aperture 2 (shown in dotted lines in Fig. 5) through the box *m*, supporting the end of shaft *n*, near which pulley *y* is fixed. Said box *m* is adapted 70 to be moved upward, carrying the end of shaft *n* and pulley *y* with it, when lever *o* is swung toward it, causing said box to ride on arm *x*, and to be allowed to drop when lever *o* is swung from it.

The operation of my improvements is as follows: When the carriage is to be started to feed toward the saw, lever *o* is moved to the position shown in Fig. 2, drawing arm *x* through the aperture 2 in box *m*, and letting the latter, the end of shaft *n*, and pulley *y* drop, and permitting the periphery of said pulley to bear against pulley *D*, thereby rotating the latter and shaft *a* and moving the carriage, as above stated. At the same time that pulley *y* is allowed to drop, 85 as just stated, by said movement of lever *o*, the idler *z* is, by the same movement of said lever, lifted away from the belt *e*, letting the latter run slack on pulley *D*, and offer no impediment to the rotation of said pulley in a 90 contrary direction to the movement of said belt. When it is desired to back off the carriage, lever *o* is swung toward box *m*, thereby raising pulley *y* away from pulley *D* and forcing the idler *z* upon belt *e*, and the latter 95 then drives pulley *D* and shaft *a* in a contrary direction from that in which pulley *y* rotated it, thereby running the carriage back. Thus, by means of a single pulley, *D*, on shaft *a*, capable of being rotated in two directions by pulley *y* and belt *e*, the carriage is easily run 100 in both directions, and the construction of the

feed mechanism in mills of this class is much simplified.

What I claim as my invention is—

1. In a saw-mill carriage-feeding device having suitable driving mechanism, a grooved pulley on the driving-shaft having a belt, *e*, running in said groove, a pulley with a rib on its face adapted to enter the groove above the belt, said pulley being mounted on a movable shaft, and shifting mechanism, substantially such as described, all the above elements in combination, so that the movable pulley may be thrown into operation and the belt loosened, or the pulley thrown out and the belt tightened by shifting the parts, substantially as set forth.

2. In a saw-mill carriage, the grooved pulley on its shaft, the belt running in said groove and connecting with the saw-arbor, the ribbed pulley on its adjustable shaft, the rib adapted to engage the groove in the first-mentioned pulley, the adjustable bearing operated by the hand-lever, and the belt-tightener, also operated by the hand-lever, all the elements combined, arranged, and operating substantially as shown and set forth.

OLIVER S. HUTCHINSON.
